UNITED STATES PATENT OFFICE.

FRANK E. HOUSH, OF WINTHROP, MASSACHUSETTS.

WALLET.

1,091,138.

Specification of Letters Patent. Patented Mar. 24, 1914.

Application filed December 19, 1912. Serial No. 737,766.

To all whom it may concern:

Be it known that I, FRANK E. HOUSH, a citizen of the United States, residing at Winthrop, in the county of Suffolk and 5 State of Massachusetts, have invented new and useful Improvements in Wallets, of which the following is a specification.

My invention is a wallet designed to receive photograph films, newspaper clippings, 10 or other articles which it is desired to store in orderly fashion.

Figure 1 is a perspective view of my wallet in use; Fig. 2 is a perspective view of the index pack, with the closure cover turned 15 in parallel relation, and the index pack ready to be inserted in the cover portion; Fig. 3 is a plan view of the closure cover arranged in crossed position; Fig. 4 is a perspective view of the filled index pack, 20 after its removal from the cover portion, with the closure cover turned in crossed position, ready for folding about the pack; Fig. 5 is a perspective view showing the index pack closed for storing; and Fig. 6 25 shows the wallet of Fig. 1, in closed position.

My new wallet is made up of a cover portion and a removable index portion composed of a multiplicity of leaves, bound at one edge and suitably indexed on their upper 30 edges. The cover portion is made up of a suitably hinged strip 1, creased to fold on the lines marked 11. To this is secured a box 2 having upstanding sides 3. The sides 3 stand at a height equal to the top of the 35 index member 4, which is formed by binding one edge of a pack of sheets of suitable material firmly together, the opposite edges being suitably indexed by figures or letters. To this pack when bound is preferably se- 40 cured a closure cover 5, 6, substantially as shown in Fig. 2, for a purpose hereinafter to be described, this cover being made of flexible stock and so creased that it may be folded when desired against the side of the 45 pack. The main cover strip 1 is shown as divided by folding creases or hinges into three whole and two half flaps marked a, b, c, d, e. The box 2 is preferably mounted and secured upon flap c, with its ends pro- 50 vided with upstanding projections 3, the height of the projections 3 corresponding to the length of the flaps b, d, so that when the flaps b, d, are turned up they will cover the front and back of the pack and the flaps a, 55 e, can be turned over the top and engaged

by suitable fasteners, as, the snap buttons, x, the edges of the flaps a, b, d, e, engaging the ends and sides of the parts 3 to form a firm, right angled box or cover. The specific ar- 60 rangement is not of course essential, since the strip 1 could be scored, and the box 2 mounted so that the half flaps would meet upon the front of the box and the top would be covered by a whole flap.

The index pack, as has been said, is made 65 up of a multiplicity of single sheets bound together at one side, which in use is the bot- tom of the pack. This bottom side is, as is customary, extended by spacing the sheets so that the bottom side is as thick as the body 70 of the leaves will be when extended by the insertion of the articles to be stored. The closure cover is made up of two strips, 5, 6, pivotally connected by an eyelet 55. When the index pack is in the box 2, the strips 5, 6, 75 are arranged in parallel relation, as indi- cated in Fig. 2. The outer cover 1 and the box 2 with its ends 3 having been secured to- gether, the index pack, with its attached closure cover is forced into the box 2, the 80 bound side being at the bottom, and designed to be of a size to fit the box 2 with a fric- tional fit.

The index pack it will be observed is forced into the box 2 and obviously, if it is 85 desired, can be removed by pulling it out. When in place however the open sides of the index pack are closed by the upstanding ends 3, so that the contents cannot escape 90 sidewise. These ends 3 also coöperate with the outer cover 1 to give the closed wallet a firm, rectangular and non-collapsible body and serve also to give a firm interior resist- 95 ance against which the snap fasteners may be engaged.

When the index pack is filled it is removed from the cover 1, 2, 3, and the closure cover 5, 6, is turned to cross position as shown in Fig. 4, pivoting on the eyelet 55, the bottom of the pack being adhesively fixed to fold 100 b^x of strip 5, fold a^x of that strip covering the front of the pack, fold c^x the back, fold d^x the top and fold e^x overlaps the front and engages fold a^x by means of the tongue x' and slot x². Fold h of the strip 6 covers the 105 back of the pack, folds g and i the ends and folds f and j overlap on the front and en- gage by means of the tongue x' and slot x².

By this arrangement it is possible to have, without undue expense, a substantial cover 110

to receive the material at a particular time being accumulated and stored, as for example, photographic films, which, when the pack is filled, may be removed and stored, 5 leaving the outer box cover ready to receive an empty index pack for convenient filing of new films, or to have a previously filled pack inserted for convenient finding of required films, and this is the preferable form of my 10 device.

When the index pack is in place in the cover as shown in Fig. 1, the closure flaps d^x and e^x of strip 5 and i and j of strip 6 which are at the back of the index pack, are folded 15 backward and their ends inserted in the box 2, in order that they may not project upward or over the top of the index leaves, in an inconvenient manner.

I claim:

The combination of an outer cover made 20 up of a box having upstanding ends and an outer strip secured to the box and hinged to fold about it and its ends and an index pack formed of a pack of leaves bound together at one edge and designed to fit within the 25 box, the upstanding ends closing the side edges of the leaves and the outer strip detachably covering the upper ends of the leaves and the front and back of the box.

Signed by me at Boston, Mass., this 16th 30 day of December, 1912.

FRANK E. HOUSH.
